[57] CLAIM

The ornamental design for a projection television receiver, as shown and described.

DESCRIPTION

FIG. 1 is a front, top and right side perspective view of a projection television receiver showing our new design with a cover and screen in raised position;

FIG. 2 is a rear, bottom and left side perspective view thereof;

FIG. 3 is a view, similar to FIG. 1, with a cover closed, screen hidden and handle extended; and

FIG. 4 is a rear, top and left side perspective view thereof.
